OTTO PABST AND CARL F. SEIBERT, OF HAMILTON, OHIO, ASSIGNEES TO NILES-BEMENT-POND COMPANY, OF NEW YORK, N. Y., A CORPORATION OF NEW JERSEY.

HYDROSTATIC PRESS.

Application filed February 17, 1926. Serial No. 88,963.

This invention relates to hydrostatic presses and in particular to a press of this type adapted for pressing car and locomotive wheels upon their axles.

5 An object of the present invention is to provide improved fluid operated means for quickly returning the ram to its retracted position after it has been forced forwardly during its operative stroke, to re-position it for 10 a second operation.

Another object of the invention is to provide a small cylinder adjacent the main plunger or ram cylinder in which is movable a piston flexibly connected to the ram so that movement of this piston in one direction will force 15 the ram to its returned or inward position.

A still further object of the invention is to provide controlling means for admitting and exhausting fluid to and from this auxiliary cylinder by means of the operation of the controlling valve for admitting fluid to the main 20 plunger or ram cylinder.

Another feature of importance is that fluid 25 for returning the ram is supplied from a pressure tank containing fluid for rapidly advancing the ram during the initial portions of its forward stroke, a four-way valve being used to control the admission of fluid to the main and auxiliary cylinders.

30 With these and other objects in view, our invention consists in the feature of the construction and operation set forth in the following specification and illustrated in the accompanying drawing.

35 In the accompanying drawing annexed hereto and forming a part of this specification, we have shown our invention embodied in a hydrostatic press of the horizontal type adapted primarily for pressing railroad car- 40 riage and locomotive wheels on their axles, but it is to be understood that many of the objects of the invention can be otherwise embodied and that the drawing is not to be construed as defining or limiting the scope of the 45 invention, the claim appended to this specification being relied upon for that purpose.

In the annexed drawing:

Figure 1 shows a side elevation of one end 50 of a hydrostatic press having the present invention applied thereto.

Fig. 2 shows a sectional view through the main controlling valve, and

Fig. 3 is a section through a four-way valve.

In the above mentioned drawing we have 55 shown but one embodiment of the invention

which is now deemed preferable, but it is to be understood that changes and modifications may be made within the scope of the appended claim without departing from the spirit of the invention.

Briefly, and in its broadest aspect, our invention comprises the following principal parts: First, a body member or headstock formed with a cylinder of large diameter; second, a ram movable in and out of such cylinder; third, a pump for forcing a fluid under extremely high pressure to said cylinder; fourth, a tank comprising fluid subjected to pressure and adapted to be admitted to said main cylinder to rapidly advance the ram 60 during portions of its forward stroke; fifth, an auxiliary cylinder attached to the main body member and having a piston therein; sixth, means for connecting this piston, preferably through flexible means, to the ram; 65 seventh, means for admitting fluid to one end of this auxiliary cylinder; eighth, a main valve for controlling the admission of fluid to or exhausting fluid from the main cylinder; and ninth, a valve actuated by movement of 70 the main control valve to admit fluid to or exhaust fluid from said auxiliary cylinder. 75

Referring more in detail to the figures of the drawing, we show the headstock end 80 of a standard form of horizontal hydrostatic press having a cylinder 11 formed centrally thereof and provided with upper and lower tie rods 12 and 13 adapted to retain a tail-piece (not shown) in fixed position relative to the body member or headstock 10. Within 85 the cylinder 11 is a ram or piston 14 having its forward end suitably formed to engage a car wheel, or other part, to be forced into or out of position. A pump 15 preferably mounted upon a side of the body member 90 10 and adapted to be operated in the usual manner by an electric motor 16 mounted upon the body member 10 is provided so that fluid under extremely high pressure may be forced into the rear of the cylinder 11. 95

To quickly advance the ram 14 when it is not subjected to high resistance by the piece being forced into or out of position, an auxiliary supply of fluid is provided in a suitable tank 18 positioned adjacent the body member 10. The upper portion of this tank 18 is connected by conduit 20 to a supply of compressed air or other fluid under pressure usually available in plants where presses such as that described are used. For this pur- 100 105 110

pose a valve 19 is provided in the fluid supply conduit 20 permitting the fluid, such as air, to be admitted to the tank 18 through conduit 21. Movement of the valve 19 to another operative position permits the pressure of air or other fluid to be released through exhaust opening 22. A discharge pipe 24 from this tank 18 permits fluid (usually water) to be admitted to the main cylinder 11 when a four-way controlling valve 25 is adjusted to one of its operative positions. Also connected to the valve 25 is a conduit 26 through which the water forced by the compressed air within tank 18 passes on its way to the cylinder 11. Within this conduit 26 is a check valve 27 preventing fluid from the main cylinder 11 passing back to the tank 18 during operation of the pump 15.

20 Cylinder 11, when the ram 14 has completed its operative or forward stroke, is adapted to be exhausted of its fluid by means of the main controlling valve 30, and the fluid discharged therefrom is adapted to flow into an open tank 31 through conduit 32 from which it may drain into the auxiliary pressure tank 18 through conduit 33. For that purpose the fluid pressure above this water or other fluid within the tank 18 is released by means of valve 19.

The above described form of hydrostatic press is one substantially as now made and has for some years been a standard method of manufacture of such machines. The ram 14, when it has completed its forward movement, has, in the past, been returned to its inner or retracted position by means of heavy counterweights passing over idler pulleys and attached to a portion of the ram 14. 40 This unduly increases the weight of the machine and also requires considerable power to raise the counterweights during the forward or operative movement of the ram. Also, unless the weights are unduly heavy, the movement of the ram to its retracted position is extremely slow. To avoid the inconveniences and loss of time occasioned by these heavy counterweights, an auxiliary cylinder 35 is mounted adjacent the body member 10 and fastened thereto in any suitable manner, as by means of bolts and tie rods 36, one only being seen in Fig. 1. This cylinder 35 may also be supported by means of a rod 36^a suitably supported upon the flooring or base 50 plate of the machine. Within this cylinder 35 which extends in a direction parallel to the ram 14, is a piston 37 having a piston rod 38 extending from one end attached by means of a chain 39, or other flexible member, to a plane 40 fastened to and moving with the ram 14. Preferably and as shown, the piston rod 38 is supported by a small cross head 41 having a roller adapted to engage the surface of the tie rods 36 so that the forward

end of the piston rod 38 is maintained in line 65 with the axis of the auxiliary cylinder 35.

In order to admit fluid to the forward end of this cylinder 35 to move the piston 37 in a direction to return the ram or plunger 14, there is provided a conduit 42 connected 70 through four-way valve 25 to the auxiliary pressure tank 18. It will be seen that when the four-way valve 25 is in one position, fluid may be admitted from the pressure tank 18 directly to the forward end of this auxiliary 75 cylinder 35 and, with the four-way valve in another position, the fluid may be exhausted from this auxiliary cylinder 35 into the open tank 31 through a special conduit 43 provided therefor. In order to actuate the four-way 80 valve, shown in cross section in Fig. 3, to control the admission and discharge of fluid to and from the auxiliary cylinder 35, the four-way valve 25 is attached by means of a lever 44 and reach rod 45 to an oscillating member 85 46 adjacent the stem of the main controller valve 30 so that when the controller valve 30 is moved to a position to advance the ram 14, the four-way valve 25 will be positioned to permit fluid to exhaust from the auxiliary 90 cylinder 35. When the ram 14 is to be returned and the pump 15 is stopped so that no fluid is admitted to the ram cylinder 11, the main controller valve 30 may be actuated 95 to move the four-way valve 25 to a position to admit fluid to the forward end of the auxiliary cylinder 35 and simultaneously open the valve 30 to exhaust fluid from the cylinder 11 into the open tank 31 through conduit 32.

On the forward end of the piston rod 38 is an abutment 50 preferably adjustable and adapted to strike a lever 51 on the valve 19 adjacent its handle. As soon, therefore, as the ram is retracted to its initial position, the abutment 50 will strike lever 51 and oscillate the valve 19. To complete the movement of the valve 19 the coiled spring 23 is provided. With the valve 19 in this oscillated position the fluid within the open tank 31 can drain 100 back into the pressure tank 18.

Preferably the lever 51 and handle 52 of the valve 19 are pivotally mounted upon the valve 19 so that they can be oscillated out of the way of the abutment so that the valve 19 105 can be moved to its other operative position to admit fluid again to the cylinder 11.

To oscillate the arm 46 to control the movement of the four-way valve 25, a worm 47 is mounted on and fixed to the stem of the valve 120 30 engaging a segmental gear 48 keyed to a shaft 49. Arm 46 is also keyed to this shaft 115 49 so that rotation of the hand wheel to actuate the valve 30 also rotates the worm 47 and oscillates the arm 44 to move the valve 25. 125

What we claim is:

A hydrostatic press comprising in combination, a body member, a cylinder thereon,

a ram movable therein, a pump adapted to force fluid into said cylinder to advance said ram, a source of fluid under pressure, means for utilizing said fluid under pressure to force said first fluid into said cylinder independently of said pump, an auxiliary cylinder, a piston therein attached to said ram, means to admit fluid to said auxiliary cylinder to return said ram, a valve for controlling

the admission of fluid to said first mentioned cylinder, and means attached to said valve to control the admission of fluid to said supplemental cylinder.

In testimony whereof, we hereto affix our signatures.

OTTO PABST.

CARL F. SEIBERT.
